tion of California

Filed July 21, 1964, Ser. No. 387,263

26 Claims. (Cl. 280—11.26)

This application is a continuation-in-part of my application S.N. 248,919, filed Jan. 2, 1963, now abandoned, for Roller Skate of Molded Plastic Construction, and a continuation-in-part of my earlier application S.N. 178,961, filed Mar. 12, 1962, now abandoned for Plastic Roller Skates.

This invention relates to skates, and while principally applicable to roller skates, is likewise applicable to ice skates and other foot gear embodying clamp mechanism for securely fastening the same to the foot or shoe of a wearer. The primary object of this invention is to provide a skate or the like of molded construction, such that it can be embodied in molded synthetic resin plastic material, fabricated in any member of selected colors and shades (e.g. pastel colors) and making it possible to utilize various selected combinations of colors in a single skate.

A further and important object is to provide such a skate having an excess of ruggedness, toughness, strength and resistance to breakage, bending, and other damage.

Still another object is to provide such a skate embodying a combination of spring-loaded clamping of opposed toe and heel jaws to the foot or shoe of a wearer, together with adjustability of the skate to a range of shoe or foot sizes, such that the spring-loading may be relatively uniform for each selected shoe size adjustment within the range.

Related objects are to provide a skate which in addition to the features outlined above, is of such easy manipulation that it can be attached to the foot by a young child without assistance from an adult, and which nevertheless will cling to the foot securely, resisting any tendency for accidental dislodgement from the foot as the result of contact with obstructions or other loads that may be imposed on the skate while it is being used.

An important object of the invention is to provide a skate having the combination of shoe-sizing adjustment and spring-loaded clamping referred to above, and which, in addition, necessitates a shoe-sizing operation only once (when it is first applied to any particular shoe) and which thereafter will remain locked at the size adjustment that has been selected, while the spring-loaded clamping operation is available for each application of the skate to the shoe and each removal from the shoe.

A still further object is to provide such a skate where-in the shoe-sizing adjustment means is manipulated with extreme ease, requiring only pressure upon a latch plunger to release the same for extension or contraction of the skate to a different size adjustment.

A further object is to provide a roller skate having front wheels placed further forwardly than in a normal roller skate, thereby providing greater support for the skater's feet and better balance on the skates. This is made possible by avoiding any projections downwardly from the toe platform of the skate which might otherwise interfere with such forward positioning of the wheels.

Other objects and advantages will become apparent in the ensuing specification and appended drawing in which:

FIG. 1 is a side elevational view of a roller skate embodying the invention, with portions broken away and shown in section;

FIG. 2 is a plan view of the same, with portions broken away and shown in section;

2

FIG. 3 is a detailed fragmentary cross-sectional view taken as indicated by the line 3—3 of FIG. 2;

FIG. 4 is a detailed fragmentary cross sectional view taken as indicated by the line 4—4 of FIG. 2;

5 FIG. 5 is an inverted plan view of the skate, with a portion broken away;

FIG. 6 is a longitudinal vertical sectional view of the same taken as indicated by the line 6—6 of FIG. 5;

10 FIG. 7 is a front end view of the heel section of the skate, partially in cross-section;

FIG. 8 is a front end view of the toe section of the skate;

15 FIG. 9 is a side elevational view of a roller skate embodying a modified form of the invention, with parts broken away;

FIG. 10 is a bottom plan view of the same with a portion of one of the rollers broken away and shown in section;

20 FIG. 11 is a cross-sectional view of the same, looking forwardly as indicated by line 11—11 of FIG. 9;

FIG. 12 is a cross sectional view of the same looking rearwardly as indicated by line 12—12 of FIG. 9;

FIG. 13 is a top plan view of the same parts broken away and shown in section;

25 FIG. 14 is a sectional view of the skate of FIG. 9 in the vertical plane of its major axis;

FIG. 15 is a heel end view of the same; and

FIG. 16 is toe end view of the same.

Referring now to the drawings in detail, and in particular to FIGS. 1-8, I have shown therein, as an example of one form in which the invention may be embodied, a junior size child's roller skate of all plastic construction (with the exception of loading springs, axles, and wheel bearing washers). In a commercial embodiment

35 of the disclosed skate, the wheels are fabricated from a colored plastic material of one pastel shade, the axle hub caps and skate body and clamping jaws are fabricated of a colored plastic material of a contrasting pastel hue, and an extremely favorable eye appeal is thereby obtained. This is one of the advantages which is made possible by the molded plastic construction of the skate. Preferably the invention utilizes, as the material, a thermoplastic polystyrene molding compound of the nitro-

40 styrene group obtainable from Monsanto Chemical Co. under the trademark Lustron, having good chemical resistance, low moisture absorption and good dimensional stability, and tensile strength in the range of 5,000-9,000 pound/square inch.

45 In general, the skate comprises a platform mounted upon roller mounts A and B at its forward and rear ends respectively. The platform structure comprises, in general, an extensible bridge C embodying respective toe and heel platform sections; a pair of shoe-coupling elements consisting of a toe unit D and a heel unit E, for clamping onto a shoe or foot F; and a size-locking latch G. The latch unit G is utilized to lock the bridge C at any selected position of shoe-sizing adjustment.

50 One of the platform sections is mounted on a corresponding section of bridge C for longitudinal sliding movements to accommodate opening and closing of the jaws to receive and release a wearer's shoe. This slide-able platform section is spring-loaded toward a retracted position of minimum spacing from the opposed platform section, and from this normally retracted position it can be moved away from the other platform section by pressure applied to it by an extremity of the wearer's shoe inserted therein. The spring-loaded platform section may be either the toe platform section or the heel platform section.

platform section which is spring-loaded in relation to its respective section of the bridge C.

Briefly reviewing the operation of the skate at this point, when the skate is first applied to a shoe of a particular size, it is adjusted to that size by finger pressure against the latch G which releases the locking connection between the sections of bridge C, permitting the adjustment of the bridge C to a length best suited to that size of shoe, or a length that is most acceptable to the person that is going to wear the skates.

Once the skate has been sized to the shoe, it can be applied to or removed from the shoe any number of times simply by inserting the toe into the toe coupling unit D, grasping the heel of the skate and pulling it rearwardly, and simultaneously pushing the toe forwardly to extend the skate sufficiently to receive the shoe. For removing the skate it is only necessary to grasp the heel section, to pull it rearwardly while exerting forward pressure against the toe section, and thereby to open the skate sufficiently to slip the shoe out of the skate.

In detail, my improved skate embodies the following features of construction:

Wheel supports A and B are each of molded plastic material comprising cylindrical rims 10 integral with solid disc webs 11 which in turn are integral with hubs 12 having cylindrical bearing bores. Axles 13 of steel or other suitable bearing metal are fitted within the bearing bores of hubs 12 with just sufficient clearance for free rotation of the wheels. The plastic material of the wheels is of such different molecular structure than the steel of the axles that friction is reduced to a minimum, there is no tendency of seizure or galling between the surfaces of wheel hubs and axle, and wear is thereby minimized.

Secured on the ends of axles 13, with a press-fit, are hub caps 14 of molded plastic material against which the outer ends of hubs 12 have rotatable end-bearing engagement. The inner ends of hubs 12 bear against metallic bearing washers 15 (FIG. 3) which are pressed onto the axle 13, maintaining its ends in spaced relation to the sides of the respective section of bridge C. The press-fitted grasp of hub caps 14 on the ends of axles 13 is adequate to secure the hub caps permanently in place against any normal end load that may be applied thereto. This permanent anchorage is made possible by knurling the ends of axles 13 at 16, there being an interference fit between the diamond pointed surfaces of the knurling and the inner wall of the molded recess in each hub cap 14.

Bridge C comprises respectively a toe section 20 and a heel section 21 which embody respective beam portions of rectangular section. The toe beam section is of box beam (regular tube) structure, having flat parallel vertical side walls 22, a bottom wall which comprises flat horizontal lateral portions 23, an upwardly arched, segmental-cylindrical central web portion 24, and a flat horizontal top web 25. The toe bridge section further includes a pair of lateral slide flanges 26 projected laterally from the side walls 22 in a common plane with the central top web 25. In the forward end of the toe section is a rectangular opening 27 (FIG. 2) which accommodates the loading spring for toe coupling unit D. The forward end of opening 27 is restricted by a pair of stop lugs 28 projecting inwardly from the inner faces of side walls 22. Projecting downwardly from the center of the forward end of top web 25 is spring anchor lug 29. The beam of heel section 21 is slidably telescoped in the box beam of the toe section 20 of the bridge, and is joined thereto by the latch G.

The rear end of the box beam portion of toe section 20 is slanted downwardly and rearwardly at 30, and is provided with notches 31 in the upper corners of side walls 22 and with strengthening gussets 32.

In the forward portion of the toe bridge section is a downwardly projecting integral axle mount 33 of triangular box form with upwardly diverging forward and rear

walls and parallel vertical side walls formed as downward continuations of the side walls 22 of the box beam section. The upwardly diverging fore and aft walls of axle mount 33 are joined by a segmental-cylindrical bottom web 34 in which the axle 13 is snugly nested, there being an interference fit between the lower surface of the axle and web 34, the axle being pressed into place, and thus a frictional grip of the web 34 against the axle is provided to hold the axle against turning. Washers 15 are likewise pressed onto the axle 13 to maintain them fixed in properly spaced positions which in turn provide fixed spacing between the washers 15 and the hub caps 14 with ample clearance between these parts and the ends of wheel hub 12 so that the latter may rotate freely without end drag.

The ends of web 34 are notched inwardly at 35 (FIG. 5) to facilitate forcing the axle through the ends of mount 33 without causing the ends to be marred by breaking small chunks out of these ends.

In the arched bottom web 24 of the box beam section is a longitudinal slot 36 having enlarged circular end openings 37 and segmental circular intermediate notches 38 in opposed pairs, equally spaced from the end openings 37 and from one another, thus providing a series (four shown) of latch apertures 37 and 38.

Heel bridge section 21 comprises a solid rectangular beam member 40 of I-beam section (FIG. 7) embodying a central web 41 which is enlarged approximately midway between the ends of the beam (FIG. 4) to provide an integral cylindrical tubular vertical boss 42 having its upper end closed by a head 43 and an open lower end receiving the latch element G. Head 43 has a downwardly projecting integral spring pilot 44. Flat horizontal flanges 45 provide the top portion of the I-beam section and the bottom includes an upwardly arched web 46 having flat horizontal side flanges 47 which are in slidably engagement with the lateral bottom portions 23 of the box beam of toe bridge section 20.

The arching of bottom web 46 conforms to the arched contour of box beam bottom 24. The arching of bottom web 24 strengthens it to resist downward pressure by the bottom member 46 of bridge section 21. Also, it provides a higher position for a button of latch element G so that it need not project below the bottom level of beam section 20 (or minimizing such projection).

In the forward half of bridge section 21, at the top thereof, is a longitudinal channel 48 communicating with the opening 27 of forward bridge section 20 and cooperating therewith in accommodating the toe coupling unit loading spring. Channel 48 has reinforced side wall members 49 (FIG. 7) offset laterally from central vertical web 41. Beam section 21 has a closed forward end defined by integral wings 50 disposed on an upward and forward incline, extending the full width of top and bottom webs 45 and 46 (FIG. 6).

At its rearward end, the heel bridge section includes an integral axle mount 51 of upwardly opening V-shape, with a semi-cylindrical bottom web 52 against which the rear axle 13 is press fitted the same as in the mounting of the forward axle 13. The upper extremity of rear wheel mount 51 merges with a rear platform section 53 including lateral wing portions projecting from the respective sides of the mount 51 and integral therewith. A reinforcing skirt 54 is integral with and projects downwardly from the margin of rear platform section 53. A rigid heel band 55, upwardly arched as seen looking rearwardly in FIG. 7, has respective side arms curved outwardly, downwardly and forwardly from the crest portion 56 of the heel band. The crest portion 56 is provided on its inner face with laterally opposed pairs of lips 57 for retaining engagement with the upper margin of the heel portion of a shoe upper. The crest portion 56 has an

upward and forward curvature conforming approximately to the average vertical contour of the shoe heel upper.

Toe coupling unit D comprises a forward platform section 60 and an upwardly arched toe stirrup 61 integral with the forward portion thereof. Toe platform section 60 includes a flat horizontal plate 62 and an integral marginal reinforcing apron 63 having a horse-shoe configuration. Platform section 60 is provided with integral slide channels 64 in opposed, parallel relation, the forward ends thereof being integrally joined to reinforcing apron 63 and the rear ends thereof being connected by integral bridging transverse webs 65 to the rear extremities of apron 63 (FIG. 5). At the center of platform plate 62, near its forward extremity, is a spring-anchor peg 66 (FIGS. 5 and 6) which projects downwardly through the rectangular aperture 27 of top web 25 of the forward bridge section. The slide channels 64 receive the side marginal portions of the slide flanges 29 of forward bridge section 20 with a sliding fit which is sufficiently loose to provide for the automatic spring-loaded engagement of the toe coupling unit D against a shoe toe, and yet is sufficiently snug to eliminate any objectionable lateral or vertical play between the toe coupling unit D and the toe platform section 60. This is particularly true in the vertical direction, where it is important that any vertical tilting between the toe coupling unit and the platform be avoided.

Sliding movement of toe coupling unit D relative to toe bridge section 20 is limited, both forwardly and rearwardly, by the confinement of stop lugs 28 of toe bridge section 20 between the forward web portion of reinforcing skirt 63 and a pair of stops 67 (FIGS. 5 and 6) of saw-tooth section longitudinally, integral with and projecting downwardly from the underface of forward platform plate 62, closely adjacent the inner surfaces of side wall members 22 of the box beam. The forward ends of stops 67 are vertical, for positive limiting action against stop lugs 28. Rearwardly of these forward vertical faces, the stops 67 have curved ramp faces which make it possible, during assembly, to force the lugs 28 beneath the stops 67, passage being provided by upward yielding of the plate 62 and downward flexing of stop lugs 28.

A spring-loaded connection between the toe coupling unit D and the toe bridge section 20 is provided for by a coil spring 68 having its forward and rear ends provided with eyes looped around the anchor peg 66 and the anchor lug 29 respectively, thereby drawing the toe coupling unit D rearwardly to the position shown in FIGS. 5 and 6, except when pushed forwardly by a skater's toe inserted into the stirrup section 61.

Latch mechanism F comprises a latch plunger 70 including a cylindrical cup shaped body 71 axially slidable in a cylindrical cavity 72 within boss 42 of toe bridge section 21, having a reduced locking bolt portion 73 projecting axially downwardly from body cup 71 and normally coupled in one of the locking apertures 37, 38 of toe bridge unit 21, and having a push-button head 74 which may optionally be connected to bolt portion 73 by a further reduced stem 75.

Seated within body cup 71, projecting upwardly through the open end thereof, and engaged under compression between the bottom of cup 71 and the head 43 of boss 42 is a coil spring 76, the upper end of which is centered by receiving therein the pilot 44 of beam section 21. The axial height of bolt portion 73 of the latch plunger is roughly equivalent to the thickness of arched web 24, so that it is only necessary to elevate the plunger 70 the distance corresponding to that thickness in order to release the bolt portion 73 from an aperture 37 or 38 in which it is coupled. Furthermore, the annular groove 77 defined between button 74 and the lower end of bolt portion 73 has an axial depth somewhat greater than the thickness of web 24, so that the projecting portions of web 24 between the apertures 37, 38, defining the slot 36, can pass smoothly between the head 74 and bolt 73 when the

plunger 70 has been thus raised. The proper position for locating this annular groove 77 in registration with the web projections, is determined by engagement of the upper end of the plunger cup 71 against the under surface of web 25.

In operation, the skate of my invention will remain firmly attached to a wearer's foot F, the toe of the foot being firmly held in the toe stirrup 61, and the heel H being firmly held by the heel band 55. It is to be noted that the crest portion 56 of the heel band is slanted upwardly and forwardly to overhang the corresponding inclined portion of the heel H, thus holding the heel captive and resisting any upward pull tending to release the heel from the heel coupling unit E. For a small shoe having an unusually low heel, the upper edge of the heel, at its rear extremity, will be engaged by the lips 57 to provide added retention.

In the modified form, FIGS. 9-16, the features of construction of the skate are the same as in the skate described above, with the exceptions hereinafter described, and the same reference numerals are used to designate similar features.

Instead of the I-beam section C, a solid rectangular beam body 40a is utilized, as shown in FIG. 12, and bottom wall 23a of box beam section C is flat. Axles 13a are of plastic material, molded integrally with mounts 33a and 51a which are integral with the respective beam sections. Extensions 30a of the box-beam side walls 22 are designed to project over rear axles 13a when the bridge is closed to minimum length. Instead of separate hub caps 14, the ends of axles 13a are expanded by hot-pressing to provide integral heads 14a.

The latch slot 36a is provided with spaced rectangular notches 38a which are adapted to receive respective dogs 58 which are formed at respective sides of a push stem 75a on the lower end of a U-shaped latch plunger 70a, and project downwardly from shoulders 71a at said lower end. Shoulders 71a seat against bottom wall 23a to determine the locking position of the plunger. Plunger 70a is vertically slidable in laterally spaced grooves 72a and a connecting slot 86 in solid beam body 40a.

Heel platform 53 is integrally connected to the rear end of solid beam body 40a by a short pillar 31, by means of which it is spaced above the beam body 40a so as to clear the top web 25 of box-beam 20.

I claim:

1. In an adjustable-length skate, in combination: respective forward and rear beam sections, both of molded plastic material, one being a tubular box beam of generally rectangular cross-section and the other including a beam body slidable telescopically within said box beam and having upper and lower longitudinal side margins fitted in the longitudinally extending internal corners of said box beam with free-sliding clearance; locomotion supports carrying the forward and rear ends of said beam sections respectively; said box beam including a bottom web provided with a longitudinally extending latch slot having pairs of laterally opposed keeper notches and intervening pairs of keeper teeth laterally spaced, with narrowed gaps between their opposed extremities, and a latch comprising a plunger slidable vertically in said beam body and a bolt having opposite side portions thereof engageable in a selected pair of said notches to latch said beam sections to one another in a selected length adjustment, said plunger having a shouldered lower end from which said bolt projects downwardly, said shouldered lower end being normally seated upon said bottom web so as to position said bolt in said slot; said latch being yieldable upwardly in response to finger tip pressure against its lower end, to release said bolt from said notches so as to permit adjustment of the skate for length.

2. A skate as defined in claim 1, including means acting between said beam body and said latch to yieldingly bias said latch downwardly to project said bolt into said slot.

3. An adjustable-length skate of molded plastic ma-

terial comprising: respective forward and rear beam sections one of which is of rectangular box beam section and the other being a solid beam body slidably telescoped in said box beam section; said solid beam body having, intermediate its ends, a vertical plunger-guide cavity, open at its lower end; a latch plunger slideable in said cavity, having a short bolt portion of reduced width projecting downwardly from its lower end, and a push stem, further reduced in width, projecting downwardly from said bolt portion; said box beam section including a bottom wall provided with a row of spaced latch apertures and intervening narrowed gaps joining said apertures in a medial longitudinal slot along which said stem is slideable when registered therewith by raising said plunger and the top of said cavity and biasing said plunger downwardly for engagement of said bolt portion in one of said apertures to lock said beam sections against relative longitudinal sliding movement.

4. A skate as defined in claim 3, wherein said plunger has a lower end shoulder from which said bolt portion projects, said shoulder normally abutting said bottom wall to position said bolt in the plane of said bottom wall.

5. A skate as defined in claim 4, wherein said bottom wall is transversely arched upwardly to provide a longitudinal channel in which said stem is largely contained.

6. A skate as defined in claim 3, wherein said solid beam body is of I-beam section including a vertical medial longitudinal web having an integral vertical boss in which said cavity is formed.

7. In an adjustable-length skate of molded plastic material: a bridge comprising respective forward and rear beam sections having remote ends provided with respective locomotion supports and with shoe-coupling jaws; one of said beam sections having a plunger-guide cavity extending substantially normal to the longitudinal axis of said bridge and having an open end, and the other beam section having a wall adjacent said open end, said wall having a row of spaced latch apertures and intervening narrowed gaps joining said apertures to collectively define a slot communicating with said open end and extending parallel to said longitudinal axis; a latch plunger axially slideable in said cavity, having an outer end provided with an offset shoulder normally abutting said wall to dispose said plunger in a locking position, having a reduced bolt portion projecting from said shoulder and receivable in a selected one of said apertures when said plunger is in said locking position, and having a stem projecting axially beyond said bolt portion, said stem having a further reduced width such as to pass freely through said gaps from one aperture to another when disposed in said slot; and means in said cavity yieldingly loading the inner end of said plunger to normally position said bolt portion in one of said apertures, with said stem projecting externally of said slot, said bolt portion having a short length not substantially longer than the thickness of said walls, whereby pressure against the end of said stem to effect a short inward movement of said plunger, will release said bolt portion from said slot and dispose said stem in said slot so as to permit said beam sections to be slidably adjusted to vary the length of said bridge.

8. A skate as defined in claim 7, wherein said plunger is in the form of a cylindrical cup, wherein said loading means is a coil spring largely contained in said cup, and wherein said first named beam has a web closing the inner end of said cavity and providing an abutment for the projecting end of said spring.

9. A skate as defined in claim 7, wherein said stem has on its outer end an integral head of a size such as to pass through one of said apertures for assembly and separation of said beam sections.

10. In an adjustable-length skate, in combination: a bridge comprising respective forward and rear beam sections, one being tubular and of non-circular section and the other being slidably and non-rotatably fitted within said tubular section and having a plunger-guide cavity

extending substantially normal to the longitudinal axis of said bridge and having an open end, said tubular beam section having a wall adjacent said open end, side wall having a row of spaced latch apertures and intervening narrowed gaps joining said apertures to collectively define a slot communicating with said open end and extending parallel to said longitudinal axis; a latch plunger axially slideable in said cavity, having an outer end provided with an offset shoulder normally abutting said wall to dispose said plunger in a locking position, having a reduced bolt portion projecting from said shoulder and receivable in a selected one of said apertures when said plunger is in said locking position, and having a stem having a further reduced width such as to pass freely through said gaps from one aperture to another when disposed in said slot; and means in said cavity yieldingly loading the inner end of said plunger to normally position said bolt portion in one of said apertures, with said stem projecting externally of said slot, said bolt portion being releasable from said slot in response to finger pressure against said stem, disposing said stem in said slot so as to permit said beam sections to be slidably adjusted to vary the length of said bridge.

11. An adjustable-length roller skate of molded plastic material comprising: respective forward and rear beam sections coupled to one another for relative longitudinal sliding movement; integral axle mounts on the remote ends of said beam sections, said mounts each being of hollow V-section comprising respective forward and rearward walls converging downwardly and joined at their lower extremities by a semi-cylindrical integral web, and vertical side walls integrally bridging the respective side extremities of said forward and rearward walls, said side walls having respective axle apertures tangent to the inner surface of said web; a metal axle extending through said apertures, snugly fitted therein, and in compressive engagement with said inner web surface whereby to secure said axle against rotation; wheels journaled on the ends of said axles; toe and heel platform members, one of said platform members being constituted by integral shelf elements projecting laterally from the upper margin of the axle mount of one of said beam sections, and the other platform member being a separate part having integral opposed parallel longitudinal slide channels depending from its lower face; the other beam section having along its upper side margins, respective lateral slide flanges received in said slide channels and coupling said other platform member to said other beam section for longitudinal sliding movement thereon.

12. An adjustable-length skate of molded plastic material comprising: respective forward and rear beam sections having respective axle mounts at their remote ends and having their other ends slidably coupled to one another, one of said beam sections being of box-beam section and the other embodying a solid beam body telescoped in said box-beam and provided with a medial longitudinal upwardly opening channel in its coupled end; said box-beam section including a horizontal top web partially covering said channel and provided in its forward portion with a longitudinal slot registering with said channel, and, adjacent the rear extremity of said slot, with a downwardly projecting spring anchor pin; a platform section seated on said top web coupled to said box-beam section for relative longitudinal sliding movement, having a shoe-coupling jaw projecting upwardly therefrom and having an integral spring anchor pin projecting downwardly through said slot into said channel; and a coil spring disposed in said slot and channel, its respective end anchored to said anchor lug and anchor pin respectively, and spring-loading said platform and jaw for yielding coupling engagement with an extremity of a shoe.

13. An adjustable skate as defined in claim 12, including a second platform section integral with the remote

end of the other beam section and provided with a shoe-coupling jaw in opposed relation to said first mentioned jaw, for coupling engagement with the other end of a shoe.

14. A skate as defined in claim 13, including a spring latch for coupling said beam sections to one another in selected positions of shoe-sizing adjustment, said latch being releasable in response to finger tip pressure.

15. In a skate, in combination: an adjustable-length bridge comprising a box beam section and a solid beam section telescoped therein, said beam sections having locomotion supports at their respective ends; said solid beam section having an integral platform section; a separate platform section slidably seated on the upper wall of said box beam section, said platform sections having respective shoe-coupling jaws, said separate platform section and box beam section having longitudinal inter-engaged slide means coupling said separate platform section to said box beam section for longitudinal sliding movement thereon; said upper wall having, in its end remote from said integral platform section, a longitudinal slot, open at the adjacent end thereof; a coil spring disposed in said slot, its ends anchored to said separate platform section and box beam section respectively, and acting in tension to spring-load said separate platform section toward said integral platform section; opposed integral stop lugs on said box beam section at the outer end thereof, projecting into said slot; and stops on the underside of said separate platform section, engageable with said stop lugs to limit outward movement of said separate platform section.

16. A skate as defined in claim 15, wherein said stops are of saw-tooth form longitudinally, with squared outer ends for engagement with said stop lugs and ramps tapering to their inner ends, for riding over said stop lugs with a deflecting action during assembly of said separate platform section to said box beam section, said stop lugs being disposed in the plane of said upper wall.

17. In an adjustable-length skate, in combination: respective forward and rear beam sections, both of molded plastic material, one being a tubular box beam of generally rectangular cross-section and the other including a beam body slidably telescoped within said box beam and having upper and lower longitudinal side margins fitted in the longitudinally extending internal corners of said box beam with free-sliding clearance; locomotion supports carrying the forward and rear ends of said beam sections respectively; a pair of integral slide flanges projecting laterally from the top of said box beam in a common horizontal plane; an integral molded plastic foot platform-clamp jaw unit mounted upon said box beam and having on its underside integral laterally-spaced L-section slideways coupled to said slide flanges for longitudinal sliding movements on said box beam, said beam body having an integral opposed foot clamp; a tension spring loading said platform-clamp jaw unit in foot-engaging direction, said spring having its one end anchored to said foot platform-clamp jaw unit and its other end anchored to said box beam; and latch means for securing said beam sections to one another in selected relative positions of foot-sizing adjustment.

18. In an adjustable-length skate, in combination: respective forward and rear beam sections, both of molded plastic material, one being a tubular box beam of generally rectangular cross-section and the other including a beam body slidably telescoped within said box beam and having upper and lower longitudinal side margins fitted in the longitudinally extending internal corners of said box beam with free-sliding clearance; locomotion supports carrying the forward and rear ends of said beam sections respectively; a pair of integral slide flanges projecting laterally from the top of said box beam in a common horizontal plane; an integral molded plastic foot platform-clamp jaw unit mounted upon said box beam and having

5 on its underside integral laterally-spaced L-section slide-ways coupled to said slide flanges for longitudinal sliding movements on said box beam, said beam body having an integral opposed foot clamp; a tension spring loading said platform-clamp jaw unit in foot-engaging direction, said spring having its one end anchored to said foot platform-clamp jaw unit and its other end anchored to said box beam; said beam body having in its upper side a longitudinally extending channel in which said spring is received; and means for securing said beam sections to one another in selected relative positions of foot-sizing adjustment.

19. A skate as defined in claim 18, wherein the means anchoring said ends of the spring consists of an integral anchor element projecting downwardly from the underside of said platform-foot clamp unit and receivable in said channel space, and an integral lug on said box beam.

20. A skate as defined in claim 19, wherein said platform-clamp jaw unit and said channel are positioned at 10 the toe end of the skate, wherein the forward end of said channel is open and said downwardly projecting anchor element is movable forwardly out of said channel.

21. A skate as defined in claim 20, wherein the forward portion of said top web of the box beam is cut 15 away to provide a space in which said downwardly projecting anchor element and a portion of said spring are receivable, and wherein said lug is attached to said top web of the box beam at the rear end of said cut-away space.

30 22. In an adjustable-length skate, in combination: respective forward and rear beam sections, both of molded plastic material, one being a tubular box beam of generally rectangular cross-section and the other including a beam body slidably telescoped within said box beam 35 and having upper and lower longitudinal side margins fitted in the longitudinally extending internal corners of said box beam with free-sliding clearance; locomotion supports carrying the forward and rear ends of said beam sections respectively; a pair of integral slide flanges projecting laterally from the top of said box beam in a common horizontal plane; an integral molded plastic foot platform-clamp jaw unit mounted upon said box beam and having on its underside integral laterally-spaced L-section slideways coupled to said slide flanges for longitudinal sliding movements on said box beam, said beam body having an integral opposed foot clamp; a tension spring loading said platform-clamp jaw unit in foot-engaging direction, said spring having its one end anchored to the underside of said foot platform-clamp jaw unit and its other end anchored to the top web of said box beam, said top web and beam body having respective registering longitudinal slot and channel spaces cooperatively receiving said tension spring; and latch means for 40 securing said beam sections to one another in selected relative positions of foot-sizing adjustment.

23. An adjustable-length skate of plastic material comprising: respective forward and rear beam sections one of which is of rectangular box-beam section and the other embodying a beam body of solid rectangular section slidably telescoped in said box-beam section; said beam sections having, at forward and rear ends of the skate, respective integral axle trunnions projecting laterally therefrom; roller wheels journaled on said trunnions; one of 45 said beam sections having laterally projecting integral longitudinal flanges at the upper extremities of its respective sides; respective shoe-clamping units, one of which is a separate molded plastic part including a platform slidably resting on said flanges, a pair of laterally opposed slide shoes of L-bar form integral with the under side of said platform, projecting downwardly and in slidably embracing engagement with the sides and under faces of said flanges to slidably couple said clamping unit to said one beam section; the other of said clamping units being integral with the other beam section; and

means spring-loading said one clamping unit toward the other clamping unit.

24. An adjustable-length skate comprising: respective forward and rear beam sections of molded plastic material, one of which is of rectangular box-beam section and the other embodying a solid beam body slidably telescoped in said box-beam section; said beam sections having, at forward and rear ends of the skate, respective integral axle trunnions projecting laterally therefrom; roller wheels of molded plastic material, of solid thick disc structure, journaled on the respective axle trunnions; said box-beam section having a horizontal top web provided with a median longitudinal slot opening into one end thereof; said solid beam body having, at one end thereof, a median, longitudinally extending neck of elongated horizontal section slidably fitted in said slot; a fixed platform integral with the upper end of said neck and projecting laterally therefrom; a shoe gripping jaw integral with and projecting upwardly from the respective sides of said platform; and a separate shoe gripping unit at the other end of said skate, embodying means connecting the same to said box beam section for longitudinally sliding movement; and means spring-loading said separate gripping unit toward the other gripping unit for yielding gripping of a shoe between said units.

25. An adjustable-length skate of plastic material including spring-loaded shoe clamping means and a supporting beam comprising respective forward and rear beam sections one of which is a box-beam, the other embodying a solid beam body slidably telescoped in said box-beam; said beam sections having, at forward and rear ends of the skate, respective integral axle trunnions projecting laterally therefrom; roller wheels journaled on said trunnions; said box-beam section having a bottom web provided with a longitudinally extending slot the sides of which are defined by respective laterally opposed keeper notches and intervening laterally opposed keeper teeth; said solid beam body having, intermediate its ends, a slideway disposed in a transverse vertical plane; a latch slidable vertically in said slideway and having, at its lower end, laterally opposite dogs receivable in a selected pair of keeper notches; and spring means acting between said solid beam body and said latch, exerting yielding downward pressure against the latch to normally maintain it in locking engagement between adjacent pairs of keeper teeth, while yielding to upward manual pressure against said latch such as to re-

lease it from such engagement and thereby to permit extension or contraction of said beam sections relative to one another.

26. In an adjustable-length skate, in combination: respective forward and rear platform sections, both of molded plastic material; a bridge beam secured to one of said sections and slidably coupled to the other section, said bridge beam including a web portion provided with a longitudinally extending latch slot having pairs of laterally opposed keeper notches and intervening pairs of keeper teeth laterally spaced, with narrowed gaps between their opposed extremities; and a latch element including a bolt portion shiftable vertically between a normal position engaged in a selected pair of said keeper notches and a position released from said notches so as to permit movement of said bridge beam relative to said latch bolt, said latch element being carried by said other platform section and spring-loaded toward said normal position so as to lock said bridge beam and said other platform section in a selected position of relative adjustment, said latch element further including a push-button portion for finger tip engagement in opposition to said spring-loading to move said bolt portion to its said released position.
